[57] CLAIM

The ornamental design for a combined spout and water control handles, as shown and described.

DESCRIPTION

FIG. 1 is a top plan view of a combined spout and water control handles showing my new design;
FIG. 2 is a front elevational view thereof;
FIG. 3 is a rear elevational view thereof;
FIG. 4 is a side elevational view of one of the handles thereof;

FIG. 5 is a left side elevational view of the spout thereof, the right side being a mirror image of the left side shown.

The fragmentary broken line representation of a lavatory basin in FIGS. 2 and 3 is for purposes of illustration only and forms no part of the claimed design.
